(57) **CLAIM**

The ornamental design for a detection device for trace elements as shown and described.

DESCRIPTION

FIG. 1 is a perspective view of a detection device for trace elements showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is second perspective view thereof; and,

FIG. 9 is third perspective view thereof.

The broken lines shown in the figures are for the purpose of illustrating portions of the detection device for trace elements and form no part of the claimed design.
